UNITED STATES PATENT OFFICE

WILLIAM H. CARSON, OF NORMAN, OKLAHOMA

FORMING MACHINE FOR POP CORN AND THE LIKE

Application filed July 25, 1927. Serial No. 208,332.

My invention relates to improvements in machines for compressing and shaping popcorn into convenient packages for marketing, handling and consuming, and for the holding of a prize therein.

The objects of this invention are to provide a machine of the character described which will be new, efficient and of utility, and adapted to form pop-corn and other like confections into a cone shaped body having a hemi-spherical top; to form and leave a depression or cavity in the said hemi-spherical top for the insertion of a small token or prize; to so form said cavity as to facilitate the handling and to expedite the consumption of the popcorn or other confection contained in the package formed; also to provide a machine which may be operated either by hand and foot, or automatically, when attached to a proper conveyor and operating system.

With these and other objects in view, the invention consists in the construction and novel combination of parts hereinafter fully described, illustrated in the accompanying drawings, and pointed out in the claims here-to appended; it being understood that various changes in the form, proportion, size and minor details of construction, within the scope of the claims, may be resorted to without departing from the spirit or sacrificing any of the advantages of the invention.

In the present form of machine the hand and foot operated unit is illustrated showing the preferred embodiment in the accompanying drawings in which: Figure 1 is a front elevation of the pop-corn molding machine, omitting the treadle and supporting legs; Fig. 2 is a perspective view of the pop-corn shown pressed into the containers; Fig. 3 is a side elevation of the machine; Fig. 4 is a perspective of the rotating or turning means for the plunger; Fig. 5 is an enlarged sectional view through the plunger showing the electrical heating element; Fig. 6 is a plan view of Fig. 1 with upper portion of the machine removed; Fig. 7 is a sectional view through the lower die or cone carrier; Fig. 8 is a side elevation of the complete machine showing foot operating means.

The machine will be hereinafter described

as employed for forming cones of pop-corn, but it is not intended thereby to limit this invention to such use, since it will be evident that the machine can be used for the forming of other things as well.

Like characters of reference designate like parts in all the figures.

In the employment of the invention illustrated in the accompanying drawings, the figure 1 represents the base or frame upon which the parts of the machine are mounted, which is preferably supported by legs 2 as shown in Fig. 1 and Fig. 8. The base of the machine may be of wood or of any other suitable material. The vertical supporting frame 3, consisting of the vertical side members 4 and 5 and the top horizontal cross member 6 is rigidly attached to the base 1 by bolts 7 and nuts 8 as shown in Figs. 1 and 3. To the cross member 6 is attached the member 9, shown in enlarged perspective in Fig. 4, having a part cylinder portion 10, provided with the curved slot 11, which virtually constitutes a cylindrical cam of approximately one-fourth revolution, thus supplying a turning means for the plunger 30, hereinafter described. The bolt holes 13 and 14, serve as a method of attaching the member 9 to the cross member 6.

Bolted directly to the base 1 is member 15, shown in elevation in Figs. 1 and 3 and in plan in Fig. 6. Member 15 forms the support for frame 3 and is attached to the said base 1 by bolts 7 as seen in Fig. 6. The bushings 16 pass through holes in 15 and serve as guides for sliding members or rods 17 of the vertically reciprocating frame 18. The rods 17 are each provided with two nuts 19, 20, at their upper ends, by means of which they are securely attached to the horizontal top bar 21, and in like manner the horizontal bottom bar 22 is secured by other nuts 19, 20 all of which is to be seen in Fig. 1. Near the center of bottom bar 22, a hinge 23 with pin 24 is provided for the attachment of a connecting rod 25. The said rod 25 having hinge connection 26 to the foot treadle 27 as seen in Fig. 8. The treadle retrieving spring 28 one end of which is attached to a cross-piece of the base 29 the other end being joined to

the treadle, serves to return the said vertically reciprocating frame 18, to the normal position as shown in Fig. 1, after being lowered in the operation of the machine.

5 Near the center of the horizontal top bar 21 of the vertically reciprocating frame 18 is securely bolted the forming plunger 30, by means of the upper flange 31 and the lock nut 32. The forming plunger 30 consists of 10 the hollow shaft-like member 33 the lower flange 34, the plunger body 35 provided with a cavity for the reception of closed end of the said hollow member 33, the said plunger body 35 having a hemispherical depression 36 formed in its extreme lower end and provided with a cone shaped point 37 for forming a depression in the top of the pop-corn package also within the hollow shaft 33 an 15 electrically operated heating element 38 for raising the temperature of the plunger body 35, all of which may be seen in the sectional view of Fig. 5. In Figs. 1 and 3 it will be seen that the plunger body 35 is provided on 20 one side of its upper end with hinge 39 and clamp 40 together with bolt and nut 41 screwed into a threaded hole in 35 and the compression spring 42, the said clamp 40 being forked and having a bearing contact upon opposite sides of flange 34 of the shaft 33. By this means the plunger body 35 may 25 be removed from the shaft 33 while the spring 42 permits limited vertical movement of the body 35 with reference to the shaft 33, and also permits the said plunger body to 30 rotate about the shaft in a horizontal plane.

On the side opposite the hinge 39 the plunger body 35 is provided with a threaded boss 43 into which is screwed the pin 44. The smooth rounded outer end of the said 40 pin 44 is suited to fit in the slot 11, of the member 9. As the frame 18 to which the forming plunger is attached is carried downward by means of the foot treadle 27 and its connections the pin 44 traveling in the cam-like slot 11 causes the forming plunger 30 to 45 turn approximately one-fourth revolution, the purpose of which will be hereinafter explained.

Movably mounted between guides 45 held 50 down by bolts 46 to member 15 is the cone carrier 47 best shown in Figs. 1, 3 and 6 and in section on Fig. 7. The cone holder 48 is provided with beveled edge flanges 49 resting on the member 15 and held down by 55 beveled edges of the guides 45, thus permitting the carrier 47 to have motion in horizontal plane. Hinged to the cone holder 48 is a hopper 50 being a hollow cylinder with inner beveled upper edge 51, a flanged lower 60 outer edge 52 and a sharp inner lower edge 53 projecting slightly downward within the upper edge of the cone receptacle 54 of the cone holder 48. The hopper 50 is rigidly locked to the cone holder 48 by means of the latch 55 in hinge connection

with 48 and bearing against the flange 52 of the hopper 50. The latch 55 is made narrower than the space between the hinge supports in order that a short piece of compression spring 56 may be slipped on the pivot of 70 said hinge on both sides of the said latch 55, thus permitting of a slight side-wise motion of the latch but insuring positive locking of the hopper 50 to the cone holder 48.

In order to insure proper vertical alignment of the forming plunger 30 the cone holder 48 and the hopper 50, there is rigidly bolted to the horizontal top bar 21 of the vertically reciprocating frame 18 the aligning rod 57 having the pointed end 58 which passes through the accurately located bushing 59 on the flange 49 of the cone holder 48. The upper edge of the hole in the bushing 59 is slightly flaring, which together with the pointed end of the aligning rod 57 insures positive entering of the rod into the bushing 80 and the proper alignment of the forming plunger and cone carrier.

The pop corn machine operates in the following manner. The cone carrier is moved to its outermost position in the guides 45, the latch 55 is turned so as to unlock the hopper 50, the hopper is swung about its hinge so as to permit a previously formed paper cone to be inserted in the cone receptacle 54. The hopper 50 is brought back into position and locked by means of latch 55, the sharp edge 53 of the hopper grips the edge of the paper cone as in a vise. The hopper 50 and open end of the cone are filled with syrup-coated 90 pop corn by hand. The cone carrier is now pushed underneath the forming plunger 30 and brought into perfect alignment by means of aligning rod as soon as the foot treadle is 95 pressed downward. As it descends the pin 44 moving in the slot 11 of the member 9 causes the plunger body 35 to turn one-fourth of a revolution, giving a twisting effect to the corn. This assists in forming the hemispherical top to the cone shaped confection. The 100 plunger body 35 being heated by the electrical element 38, causes the syrup on the pop corn to act more or less as a lubricant when being formed so it will slide into place more easily.

The heat also prevents the syrup from sticking to the plunger. The foot treadle is released, the plunger rises to its normal position as seen in Figs. 1 and 3 and the cone carrier is moved to the right in Fig. 3 until the flange 52 of the hopper 50 strikes the stop 60. The latch 55 is turned to unlock the hopper, 110 which is then swung to the left out of the way. This releases the cone carrier from stop 60, and puts the filled cone in a position to be ejected from the machine.

The ejecting device is shown in Figs. 1 and 3 and more clearly in Fig. 7. It consists of a small cylinder 61 within the bottom of the cone holder 48 and has a hollow cone shaped opening to receive the pointed end of the 115 120 125 130

paper cone and about one-third of its axial length. A small shaft 62 integral with the cylinder passes through a hole in the bottom of the cone holder 48 and upon this shaft is placed a coiled compression spring 63 held in place by the washer and nut 64. The extreme lower end of the said shaft 62 terminates in a fork in which is placed a roller 65.

When the hopper 50 has been swung to the left in Fig. 3 so as to be released from the stop 60 the cone holder is moved still farther to the right until the roller 65 mounts the incline 66. This raises the ejector cylinder 61, which supports the now filled paper cone and if the holder is moved rapidly the ejector will throw the cone upward out of the holder with considerable force.

The incline 66 is a part of the cross frame member 67, bolted to the L-shaped vertical members 68, the tops of the said members 68 are fastened by the bolts 69 to both the member 15 and the guides 45 and serve both as a means of fastening 45 to 15 as well as a stop to prevent the cone carrier 47 from passing out 25 of the guides to the right. Stops 70 on the left end of the guides 45 as seen in Fig. 6 prevents the carrier 47 from passing out of the guides to the left.

The conical point 37 centered within the hemispherical cavity formed on the lower end of the plunger body serves to form and leave a depression in the hemispherical top of the filled cone. This depression serves as a depository for a small token or prize and also facilitates the consumption of the popcorn contained in the cone shaped confection.

Having described my invention what is claimed and desired to be secured by Letters Patent, is:

1. A machine of the character described, comprising a plunger member for forming the top of a moldable mass, rotatably mounted on a vertically reciprocating frame having guide rods adapted to move vertically, means for rotating said plunger member, means for reciprocating said frame, renewable guides for said rods, and a slideable cone carrier mounted between horizontal guides on said machine and adapted to be brought under said plunger member and adapted to support and hold said mass in a preformed container while the top of said mass is being formed by said plunger, said plunger member adapted for shaping the top of and packing said mass in said container.

2. A machine of the character described, comprising a rotatably mounted plunger member rigidly supported by a vertically reciprocable frame, means carried by a stationary frame for rotating said plunger within said reciprocating frame, means for reciprocating said reciprocating frame, and a cone carrier slidably mounted between horizontal guides on said machine, said carrier adapted to support a moldable mass in a pre-

formed container and adapted to be brought under said plunger for packing said mass into said container and for shaping the top of said mass.

3. In a machine of the character described, the combination of a rotatably and reciprocally mounted plunger member for packing and forming a spherical shape to the top of a moldable mass, means for rotating and reciprocating said plunger, a slidably mounted cone carrier adapted to carry said moldable mass and to be brought under said plunger, and means for supplying heat to said plunger for expediting the forming of said mass.

4. A machine of the character described, comprising a rotatably and reciprocally mounted cylindrical plunger member having a hemispherical recess in its extreme lower end of a radius equal to that of the cylinder forming said plunger, a knife edge formed by said recess and the circumferential edge of said cylinder, means for rotating and vertically reciprocating said member, and a slidably mounted cone carrier adapted to carry a moldable mass in a preformed container, and to be brought under said plunger for packing the mass in said container and for forming a spherical top to said mass.

5. A machine of the class described, comprising a rotatably and reciprocally mounted cylindrical shaped plunger member, having in its extreme lower end a recessed hemispherical cavity, said cavity having therewithin a solid cone-shaped projection axially positioned on the vertical center line of the plunger member, means for rotating and vertically reciprocating said member the said cavity and projection providing means for giving a spherical shape to the top of a molded mass and forming a depression in the same for the insertion of a small token, the said mass being packed in a preformed cone-shaped container, and a slideable cone carrier supporting said container and disposed under the said plunger member.

6. A machine of the character described, comprising a rotatably and reciprocally mounted cylindrical shaped plunger body, means for rotating and reciprocating said body, said body having a hemispherical recessed cavity in its extreme lower end and having a solid cone shaped projecting member within said cavity for forming a depression in the hemispherical top of a moldable mass, the sharp upper edge of the said depression thus formed serving as a point of attack in masticating the molded mass, the said plunger body being provided near its top with a bifurcated clamp in hinged connection therewith adapted to attach said body to the flanged shoulder upon the shaft of the forming plunger, a bolt in threaded connection with the said plunger body having a nut and compression spring for mounting and dismounting said clamp and yieldingly hold-

- ing said plunger body against said shoulder and opposite the hinged connection of said clamp, a boss having a threaded hole, a pin disposed therewithin being adapted to be guided by the cylindrical cam-like slot in a turning means, turning means for imparting a rotating motion to the plunger body in its downward movement, to contact, pack and form a spherical top to a molded mass within a preformed cone-shaped container, and a cone carrier slidably mounted for control within guides disposed under said plunger body, said guides being provided with stops at both ends. 70
- 10 7. A machine of the character described, comprising plunger member for forming the top of a moldable mass rotatably mounted on a vertically reciprocating frame having guide rods adapted to move vertically, means for rotating said plunger member, means for reciprocating said frame, renewable guides for said rods, a slideable cone carrier mounted between horizontal guides on said machine and adapted to be brought under said plunger member and adapted to support and hold said mass in a preformed container while the top of said mass is being formed by said plunger, said plunger member adapted for shaping the top of and packing said mass in said container, and means for automatically ejecting said container from said carrier when said carrier reaches its outermost throw in its slideable movement. 80
- 15 8. Organization as described in claim 7, in which said carrier is provided in its base with a cylindrical recess adapted to receive the lower portion of said container, and is also provided with a smaller central through bore, and in which said ejecting means comprises a shaft slidably mounted in said bore and extending therebelow, said shaft having a roller mounted on its bifurcated lower end and having a coiled compression spring normally holding said shaft in a downward extending position, an inclined plane member adapted for contacting said roller and raising said shaft when said carrier reaches the outermost end of its throw, said shaft adapted to contact and eject said container from said carrier when so raised. 100
- 20 9. Organization as described in claim 8, in which the carrier is provided at its top with a hinged hopper adapted to be closed upon and latched to said carrier and adapted to clamp said container rigidly within said carrier, and in which a stop is provided upon the carrier guides for stopping said carrier medially in its outward travel until said hopper has been manually swung from its latched position. 105
- 25 10. A machine of the character described, comprising a rotatably and reciprocally mounted cylindrical plunger member, having a hemispherical cavity in its extreme lower end, a downstanding conical shaped projection within said cavity, means for vertically reciprocating said plunger, and a slidably mounted carrier adapted to carry a moldable mass in a preformed container, and to be brought beneath said plunger for co-acting with said plunger in packing said mass in said container and for forming the top of said mass. 75
